UNITED STATES PATENT OFFICE.

GEORGE GRAY, OF MIANUS, CONNECTICUT, ASSIGNOR TO MIANUS MOTOR WORKS, OF MIANUS, CONNECTICUT, A CORPORATION OF CONNECTICUT.

MUFFLER.

984,212.

Specification of Letters Patent. Patented Feb. 14, 1911.

Application filed December 8, 1909. Serial No. 531,929.

To all whom it may concern:

Be it known that I, GEORGE GRAY, of Mianus, county of Fairfield, State of Connecticut, have invented certain new and useful Improvements in Mufflers, of which the following is a full, clear, and exact specification, such as will enable others skilled in the art to which it appertains to make and use the same.

10 My invention relates to a muffler for reducing the noise of the exhaust of gasoline and other internal combustion engines.

The object of the invention is primarily to reduce the noise of the exhaust as much as possible without, however, obstructing the exhaust and creating a back pressure in the working chamber. In attaining this end I cause the exhaust gases to enter the muffler through a perforate pipe or similar 20 element located under a water supply to the interior of the muffler chamber, which causes the hot gases to encounter a water spray instantly upon passing into the muffler chamber, thereby cooling and condensing the 25 gases and bringing them close to the point of atmospheric pressure. Further, by this arrangement in combination with the muffler chamber, which furnishes an expansion chamber, the gases thus cooled and reduced 30 in volume are given room to expand before finally passing from the muffler to the atmosphere. Opposite the inlet for the exhaust gases, the muffler chamber is provided with the final outlet connection and also 35 with an outlet for the water.

The invention involves other features of importance, all of which will fully appear hereinafter.

Reference is had to the accompanying 40 drawing, which represents a sectional view of the muffler according to the preferred construction.

In this drawing *a* indicates the body or muffler chamber, which is preferably in the 45 form of a cylindric drum of cast iron, provided with bossed inlet opening *a'* and a similar outlet opening *a''* respectively in its opposite ends or heads and also provided at its top near the inlet end with the bossed 50 water inlet *a³* and at the bottom near the outlet end with a bossed water outlet *a⁴*.

Threaded into the inlet opening *a'* is the 55 perforate supply pipe or thimble *b*, the inner end of which is formed with a perforate wall. This thimble *b* projects cen-

trally into the chamber of the muffler and has a union with the exhaust pipe *c* from the engine. Gases passing out at high pressure and temperature through the pipe *c* enter the pipe or thimble *b* and emerge 60 therefrom through the perforated sides and end.

d indicates the water supply pipe which may come from any suitable source, preferably from the cylinder jacket and which 65 is fastened in the inlet *a³* of the muffler chamber directly over the perforate thimble *b*. In this manner the spray of water is discharged continually on the thimble with the result that the gases escaping the perforate pipe *b* encounter the water spray and are cooled and reduced in volume while the water is evaporated or converted into vapor. This vapor mingles with the exhaust gases 70 and expands with such gases in the chamber *a*, this expansion further reducing the temperature and pressure. Such water as is not evaporated in the chamber *a* passes to the bottom of the chamber and is conducted thence by an outlet pipe *e*. The exhaust 75 gases and vapor of the water pass into the atmosphere through a pipe *f*, which is fastened in the bossed outlet opening *a''*. It will therefore appear that by means of my invention the exhaust gases are cooled and 80 hence caused to contract or reduced in volume. Simultaneously water vapor is formed which mixes with the exhaust gases and the whole mixture is allowed to expand in the chamber *a*. By these combined operations 85 the exhaust gases are brought practically to atmospheric pressure so that they may pass from the muffler with little noise. At the same time, and of equal importance, a clear passage is provided to the atmosphere 90 and back pressure in the engine is avoided. Incidentally the water cools the walls of the chamber *a* and obviates the common disadvantage of an extremely hot muffler.

Having thus described my invention, what 100 I claim as new and desire to secure by Letters Patent of the United States, is:

1. A muffler having an expansion chamber, a perforated inlet pipe for the exhaust gases, having a perforate wall at its inner 105 end, such pipe projecting centrally into the expansion chamber and discharging therein the products of combustion through the perforations, a water supply pipe discharging into the upper part of the chamber directly 110

over the perforated pipe, said chamber having an outlet for the vapor and gases at the end opposite the supply pipe and an outlet at the bottom for drawing off the surplus water.

2. A muffler having an expansion chamber, a perforated inlet pipe for the exhaust gases, having a wall at its inner end, such pipe projecting into the expansion chamber 10 and discharging therein the products of combustion through the perforations, a water supply pipe discharging into the upper

part of the chamber over the perforated pipe, said chamber having an outlet for the vapor and gases and an outlet at the bottom 15 for drawing off the surplus water.

In testimony whereof I have signed my name to this specification in the presence of two subscribing witnesses.

GEORGE GRAY.
